UNITED STATES PATENT OFFICE.

MALCOLM E. LAUNBRANCH, OF CHICAGO, ILLINOIS, ASSIGNOR TO PEERLESS ELECTRIC SIGN COMPANY, OF CHICAGO, ILLINOIS, A CORPORATION OF ILLINOIS.

ELECTRIC-SIGN SYSTEM.

1,238,027.

Specification of Letters Patent. Patented Aug. 21, 1917.

Application filed January 22, 1916. Serial No. 73,594.

To all whom it may concern:

Be it known that I, MALCOLM E. LAUNBRANCH, a citizen of the United States, residing at Chicago, in the county of Cook and State of Illinois, have invented a certain new and useful Improvement in Electric-Sign Systems, of which the following is a full, clear, concise, and exact description, reference being had to the accompanying drawings, forming a part of this specification.

My invention relates to changeable electric signs, or what might be called writing signs, and has for its object the provision of an improved system of operating and controlling signs of this character.

More in detail, my invention may be said to belong to that character of signs in which there are a plurality of sign units in each one of which units it is possible to establish selectively any letter of the alphabet or arbitrary sign, by the selection of a predetermined portion of the electric lamps or other signaling devices present in that particular unit.

In the specific embodiment of my invention at present in service there are sixty units as above outlined, preferably in four rows of fifteen each, and each unit has fifty-three incandescent lamps. By a proper selection of the lamps in each unit any letter or predetermined signal or character may be established in any given unit. There being sixty of these units, it is readily apparent that a complete sentence may be written out. In the particular form under discussion the sign is used for advertising purposes, the legend appearing upon the sign being changed every twenty seconds. It thus requires controlling apparatus of peculiar character to effect a rapid succession of different legends, and my invention herein concerns itself with the production of said controlling apparatus.

I have so arranged the controlling apparatus that a plurality of electromagnetic devices for each unit, one for each letter or character, are suitably operated through the agency of a templet or prepared plate or tape in such a manner that changes of the legend presented to view by the sign may be rapidly and instantaneously made by one operator.

I will explain one form of carrying out

my invention by referring to the accompanying drawings, in which—

Figure 1 is a fragmentary front view of a sign adapted to be controlled through the agency of the apparatus of my invention;

Fig. 2 is a diagrammatic view illustrating the electrical and mechanical principles involved;

Fig. 3 is a diagrammatic side view illustrating the mechanical operations;

Fig. 4 is a view of a modification; and

Fig. 5 is a perspective view showing the contact controlling devices.

Referring more particularly to Fig. 1, I show a sign which has a plurality of units, 1, 2, 3, 4, in four different rows, there being thirteen units in each row. Each unit 1, for instance, has fifty-three incandescent lamps so that any letter, character, or arbitrary symbol may be set out in that particular unit. The same is true of any of the other units. My improved apparatus is designed to control the lamps in these various units so that different legends may appear upon this sign successively.

Referring more particularly to Fig. 2, I have shown diagrammatically the equipment necessary to control the sign, although I do not show all of the equipment, showing merely a sufficient portion thereof to indicate all of the principles involved, omitting the merely duplicatory matter.

I might say in passing that with the arrangement of the lamps in each unit, I may obtain at least forty different letters or characters in each unit.

I have shown in Fig. 2 a portion of the units of the sign shown in Fig. 1, respectively the units 1, 2, 3 and 4, and 1^a, 2^a, 3^a and 4^a. I show a portion of the equipment necessary to operate the units 1, 2, 3 and 4, the equipment to operate the balance of the fifty two units being entirely similar and a duplication of what is here shown in Fig. 2. A key board 5 having divisions corresponding respectively to the first four units 1, 2, 3 and 4 of the sign, respectively the divisions 5^a, 5^b, 5^c and 5^d. The key board 5 is of course then extended sidewise so as to provide divisions for each one of the remaining units 1^a, etc., although herein merely a sectional view of this key board is shown. Each division has switch plungers, for instance, the switch plungers 6^a, 7^a, 8^a,

9^a and 10^a, and 6^b, etc. Each plunger such as 6^a for instance is designed to control one letter or character. In the device 5^a for instance, I have shown but five plungers. 5 Thus I will be enabled to control but five letters in the unit 1. It must be understood however and it will be clear hereinafter that there will be as many plungers as it is desired to have characters in each particular 10 unit; in fact, in the completed sign structure referred to above there are about forty plungers for each unit so that there can be about forty characters set out in each unit. Intermediate of the key board 5 and the 15 units 1, etc., I interpose switching devices respectively the switching devices 11^a, 11^b, 11^c, and 11^d. Each of these switching devices similarly to the devices 5^a, 5^b, for instance, are shown as adapted to control but 20 five lamps, these being thought to be sufficient for the purpose of understanding the invention. Each switch unit for instance consists of two end bars 12 and 13 within which are rotatably mounted control rods 14, 15, 16, 17, and 17^a. Springs 18 tend to 25 keep these control bars in the position shown in Fig. 3 against a stop 19. The control bars have armatures 20, the armatures of the various control bars being actuated by 30 electromagnets 21, 22, 23, 24 and 25. Each of the control bars has a plurality of contact fingers, for instance, the contact fingers 26, which contact fingers are adapted when 35 these control rods are rotated to engage bus bars 27, 28, 29, 30 and 31 respectively. Thus if any magnet 21, for instance, is energized (Fig. 3), then the corresponding control rod 40 14 is rotated clockwise to bring the contact fingers 26 carried by that rod into engagement with the bus bars corresponding to the 45 positions of said contact fingers, which in this case would be the bus bars 27, 29 and 31. Conductors lead from these bus bars to lamps 32, 33, 34, 35 and 36 respectively, one terminal of each of the lamps being shown connected to a battery 37, the other terminal of the battery being connected to the end frame 13. As the control rods 14, etc., are metallic 50 and have metallic engagement with the end plate 13, they are thus always connected to one terminal of the battery 37. Thus if any control rod is rotated, such as the control rod 14, for instance, lamps 32, 33 and 35 will burn, thus giving one character. As previously 55 stated there are of course fifty-three lamps in each unit, and in the preferred form hereinbefore mentioned there are forty plungers 6^a, and forty control rods of the type of the rods 14 to 17^a inclusive.

60 It will thus be seen that the actuation of either of the keys 6^a, 7^a, 9^a or 10^a secures the presentation of a distinct character in the unit 1. The bus bars 27, etc., are of course insulatingly mounted as readily apparent.

65 If it is desired to set forth a character in

each of the units 1, etc., then of course a plunger in every division 5^a, etc., must be actuated. To control the selection of the desired plungers (6^a for instance), I use a templet 38 which is perforated in a manner corresponding to the particular sentence it is desired to display by means of the completed sign. This templet is placed against a platen 39 which is then moved against the plungers 10^a, *et seq.*, and those plungers 70 which are opposite the perforations pass through and touch the metallic platen 39. Thereupon the relays corresponding to these plungers are energized by means of the circuit which extends for instance from the 80 platen 39, by way of the conductor 40, battery 41, common conductor 42, to the relay 21 for instance, conductor 43, plunger 10^a, to the platen 39.

In Fig. 4, I show a modified form of the 85 device in which relays 21 and 22 for instance both have a common armature 20^a. This common armature is provided with contact springs 26^a and 26^b so that for instance the contact fingers 26^a are arranged 90 for the letter *a*, and the contact fingers 26^b are arranged for the letter *b*. Then if the armature 20^b is tilted clockwise, as when magnet 21 is energized, the letter *b* is formed by bringing the contact fingers 26^b 95 into association with the conducting bar 27^b, for instance; whereas, if the armature 20^a is tilted contra-clockwise then the contact fingers 26^a engage the conducting bar 27^a to form the letter *a*. In this manner I 100 reduce the number of rods such as 14 by one half.

In the claims I have used the word "lamp" as meaning any individual sign element of which there are a plurality going to make 105 up a complete sign unit.

From what has been described the nature of my invention will be readily clear to those skilled in the art, as will also its various modifications and uses. Having however 110 thus described one form which my invention may take, what I claim as new and desire to secure by Letters Patent is:

1. In a device of the character described the combination with a plurality of sign 115 units each having a plurality of lamps adapted when selectively actuated to portray unlike characters, a key board having a number of divisions corresponding to the number of units, and a templet having 120 means for simultaneously selectively controlling said key board divisions.

2. In a device of the character described the combination with a plurality of lamps adapted when selectively actuated to portray 125 unlike characters, a switching device having means for selectively controlling said lamps, and a plurality of electromagnetic means for selectively controlling said switching device, said switching device comprising a plurality 130

- of bus bars, one for each lamp, and a plurality of rotatable switching rods one for each electromagnetic means, said switching rods being controlled by said electromagnetic means to control the energization of said lamps, a switchboard for controlling the selection of electromagnetic means aforesaid, and a templet for controlling the actuations of said switchboard.
- 10 3. In a device of the character described the combination with a plurality of lamps adapted when selectively actuated to portray unlike characters, a switching device having means for selectively controlling said lamps, and a plurality of electromagnetic means for selectively controlling said switching device, said switching device comprising a plurality of bus bars, one for each lamp, and a plurality of rotatable switching rods one for each electromagnetic means, said switching rods being controlled by said electromagnetic means, said switching rods having contact fingers selectively disposed so that each contact rod corresponds to a different character, a switchboard for controlling the selection of electromagnetic means aforesaid, and a templet for controlling the actuations of said switchboard.
- 20 4. In a device of the character described the combination with a plurality of sign
- units each having a plurality of lamps adapted when selectively actuated to portray unlike characters, a key board having a number of divisions corresponding to the number of units, and a templet having means for simultaneously selectively controlling said key board divisions, each division of said key board having a plurality of contact elements corresponding to the number of lamps in the corresponding sign unit.
- 25 5. In a device of the character described the combination with a plurality of sign units each having a plurality of lamps adapted when selectively actuated to portray unlike characters, a key board having a number of divisions corresponding to the number of units, and a templet having means for selectively controlling said key board divisions, each division of said key board having a plurality of control elements corresponding to the number of lamps in the corresponding sign units.

In witness whereof, I hereunto subscribe my name this 17th day of January, A. D., 1916.

MALCOLM E. LAUNBRANCH.
